(No Model.)

J. D. HALL.
WAGON.

No. 427,416.

Patented May 6, 1890.

UNITED STATES PATENT OFFICE.

JOHN D. HALL, OF ORRVILLE, OHIO.

WAGON.

SPECIFICATION forming part of Letters Patent No. 427,416, dated May 6, 1890.

Application filed March 8, 1890. Serial No. 343,121. (No model.)

To all whom it may concern:

Be it known that I, JOHN D. HALL, a citizen of the United States, and a resident of Orrville, county of Wayne, State of Ohio, have 5 invented a new and useful Improvement in Wagons, of which the following is a full, clear, and exact description, reference being had to the accompanying drawings, making part of this specification.

10 My invention relates to improvements in wagon-gear; and it consists in providing means by which the front and rear axles may be locked together in a parallel relation or at a desired angle to hold the four wheels in 15 alignment or to hold the front axle rigid with the rear axle at any desired angle within the limit of its movement.

With these ends in view my invention consists in certain features of construction and 20 combination of parts, as will be hereinafter described, and pointed out in the claims.

25 Figure 1 of the accompanying drawings is a side elevation, partly sectional, illustrating my invention; Fig. 2, a plan view, and Fig. 3 a perspective of detail. Fig. 4 is a plan view of the front end portion of the front hounds, showing the manner of connecting the tongue; and Fig. 5, the tongue-supporting plate.

30 Similar letters indicate corresponding parts in all of the figures of the drawings.

As my invention is applicable to many of the well-known wagons now in use, I will proceed with a description of my invention, referring to the wagon parts only as conjunctive thereto.

35 A represents the wagon-wheel, placed on the spindle in the usual way; B, the axle, and C the reach, connecting the rear axle (not shown) to the front by the king-bolt D in the usual way.

E represents a sand-bar of the usual form.

On the under side of the reach C is provided a spring-actuated bolt F, to slide in a 45 suitable supporting-box portion G, the rear end of said bolt to engage a series of notches J in a segmental plate K, secured to the rear portion of the front hounds L. A clevis, as M, is provided, having a front portion a, projected forward of and above the axle B, and 50 having prongs b, through which are provided

apertures d, the prongs b provided with oppositely-projecting arms e. The reach C is placed between the prongs b c and the axle B and sand-bar E. The king-bolt D is passed 55 through the sand-bar apertures d in the rear end portion of the prongs b and the front end of the reach, as shown in Fig. 1. The end portions of the arms e have a chain or link connection h with the bolt F, by which the 60 bolt may be drawn out of the notch J in the segment or rack K.

The tongue is pivotally secured to the front portion of the hounds L about the plate k, said plate having at its end portions a rounded 65 portion p, on the ends of which is provided a screw-thread, and in the central portion of said plate is provided a perforation for a tongue-bolt q. A mortise is provided in the tongue, as shown by the dotted line, into 70 which the plate k is placed and the bolt q passed therethrough. The front end portion of the hounds, having a perforation adapted to receive the rounded portion of the plate, are placed in position, as shown in Fig. 4, and 75 threaded nuts turned on to secure the parts in working position.

It will be noticed that by the provision just described the front end of the tongue may move vertically by rocking the plate in 80 the hounds and laterally by moving about the bolt q. The rear end of said tongue is adapted to embrace the front portion m of the clevis M, about which portion may be placed a coil-spring n, the lower end of which 85 rests on the top of the tongue and the upper end restrained by the upper end portion of the clevis M. The energy of the spring is exerted downwardly, by which the front end of the tongue is raised to relieve the team of 90 a portion of the weight of the tongue on the neck.

In operation, when the bolt F is in the central notch of the segment K the tongue N and reach C are locked in alignment, the front 95 and rear axles parallel, and will so remain during the progressive movement of the wagon, and in case of the front wheel striking an obstruction the blow will be resisted by the reach C, to which the axle is locked by 100 the bolt F engaging the segment K, as before stated, by which arrangement the tongue is

secured from violent lateral movement against the team; and when it is desired to change the direction of the wagon the pressure of the team on the tongue through the neck-yoke will cause the rear portion of the tongue to move a distance, for which provision is made in the connection of the tongue to the front portion of the hounds L to allow the rear end to swing the clevis M to the right or to the left a short distance. The arms e are of such length that a slight movement of the tongue will swing the arms such a distance as to draw the end of the bolt F out of engagement with the segment K. The segment may be swung a distance and the bolt dropped into another notch of the segment, by which the front axle will be locked obliquely to the reach and the rear axle, in which position the progressive movement of the wagon would describe a given circle until interrupted by the movement of the team. Thus it will be seen that the tongue, axles, and reach may be locked in position at right angles to each other; or the front axle may be locked to the reach on a line oblique to the rear axle and at any desired point of adjustment within the movement of said parts. The advantage will be apparent that while the team has perfect control to guide the wagon by the tongue the tongue is at no time free to strike the team as formerly, unless it is at the instant the bolt F is disengaged, and on whatever line or circle the wagon may be drawn the gear will always be held to the desired line by the bolt F engaging the segment K, which engagement may be made or broken at any instant by the movement of the team, causing a lateral or side movement of the front end of the tongue; but when the end of

the tongue is at rest in the neck-yoke ring, having no lateral pressure thereon, the parts will be locked together, as hereinbefore stated. 40

Having thus fully described the nature and object of my invention, what I claim as new, and desire to secure by Letters Patent, is—

1. The combination, with the front axle of a wagon, of the hounds L, the tongue N, loosely secured therein and adapted to move vertically and laterally in said hounds, the clevis M, having a front vertical portion adapted to engage the rear end of the tongue, arms 50 extending laterally therefrom, and links n, by which said arms are connected to a locking-bolt F, adapted to engage a series of notches on the rear portion of the hounds L, substantially as described, and for the purpose set forth. 55

2. The combination, with the front axle of a wagon, of the hounds L, a rack K, secured to the rear portion of said hounds, a tongue pivotally secured in the front portion of said hounds, a clevis M, pivotally secured to said axle, said clevis having arms e, and a link-connection with a spring-actuated locking-bolt F, substantially as described, and for the purpose set forth. 65

3. The combination, in a wagon, of the axle B, clevis M, and tongue N, the rear end of which engages the clevis M and spring n, substantially as described, and for the purpose set forth. 7c

In testimony whereof I have hereunto set my hand this 15th day of February, A.D. 1890.

JOHN D. HALL.

Witnesses:

J. NELSON FERRELL,
WM. A. CASE.
